UNITED STATES PATENT OFFICE.

HEBER S. NELSON, OF SALT LAKE CITY, UTAH, ASSIGNOR OF ONE-FOURTH TO ROBERT MURRAY STEWART, OF SALT LAKE CITY, UTAH.

PHONOGRAPH REPRODUCER.

Application filed April 9, 1926. Serial No. 100,961.

REISSUE

My invention relates to electromagnetic phonograph reproduction.

The object of my invention is to provide a simple and efficient means of converting 5 mechanical vibrations, such as are grooved or engraved on phonograph records, into electrical impulses; these impulses when introduced into an amplifier circuit connected to what is commonly called a loud speaker, 10 reproduce the music, voice, sounds of whatever is recorded, thus providing an instrument for such purposes which will be extremely sensitive to actuating vibratory changes.

15 Another object is to provide a spool for the coil of wire, which will not permit eddy currents of the transformer type.

Another object of the invention is to use a 20 single spool or winding and yet obtain the combined magnetic action of four pole pieces on the vibrating armature.

Another object is to provide a means of 25 centering, balancing and adjusting the armature to the most sensitive position, so as to prevent the armature from sticking to the pole pieces and to produce through the amplifier with loudness and distinctness, without distortion, such articulate or other sounds as may be imbedded on the surface 30 of a phonograph record.

With the foregoing and other objects in view, the invention consists of certain novel features of construction, combination and arrangement of parts, as will be more fully 35 described and particularly pointed out in the appended claims.

In order that my invention may be fully understood, I will proceed to describe it, having reference to the accompanying drawings, in which—

Figure 4 is a side elevation of an electromagnetic pick-up constructed in accordance with my invention. Fig. 1 is a transverse section of the same, on the line 1 1 Fig. 4 45 and looking in the direction indicated by the arrows on said line. Fig. 2 is a longitudinal section of the same, through the center of the armature and the stylus bar, on the line of 2 2 of Fig. 1 and looking in the direction indicated by the arrows on said line. Fig. 3 is a cross sectional view of the same, through the center, on the line 3 3 Fig. 4 and looking in the direction indicated by the arrows thereon; Fig. 5 is an enlarged cross 55 sectional view showing the method of pivot-

ing the armature; Fig. 5^A is a side elevation of the armature and shaft. Fig. 6 is an enlarged cross sectional view showing a modified means of pivoting the armature.

In said drawings H designates a permanent magnet of circular form, to its extremities or poles h and h' are secured the U shaped pole pieces P and P' by means of screws h h'; these pole pieces support the spool S, on which is wound the wire forming the coil of wire, the number of turns of wire being dependent upon the impedance of the circuit in which the pickup is to be used. This spool consists of a non-magnetic oblong tube with oval end pieces, the tube is 60 slotted at z Fig. 5 upon its upper side and its ends separated so as to prevent eddy currents from effecting the magnetization of the armature A. This spool is held in place by blocks b and b', which are secured to the 65 spool at each end and fit into recesses cut into the pole pieces P and P' at each of their four corners. This armature is supported by means of a shaft E. This shaft is supported at its ends by being run through apertures 70 in the walls of the tube. The armature has slotted recesses stamped into it across its exact center to admit the shaft E. One end of the armature is connected to the stylus bar B. The stylus bar is slotted at y to receive the armature. The stylus bar is pivoted by means of screws p p', Fig. 1, engaging in lugs n n'. These screws p p' are supported by the lugs o o' from the frame F. This frame is of non-magnetic material. 75 The pole piece P' is secured to it by screws r r', which hold the entire unit in the case. The screw t is also tapped into the frame. The screws t t' are for the purpose of adjusting the tension of the springs s s' which center and balance the armature in its most sensitive position. The screws t t' and the stylus bar are provided with short lugs over which the springs s s' are placed to keep them from moving out of alignment. The 80 ends of the wire from the spool S are soldered to the standards o o'. These standards are provided with suitable set screws for connecting wires to the amplifier. They 85 are also suitably insulated from each other and from the frame. A non-magnetic cover D is provided to protect the various working parts.

The operation of the electromagnetic pick-up is as follows: The stylus bar B is caused 90 to move in the slot y, thereby causing the armature A to move in the slot z. This movement 95 causes the wire to be wound on the spool S. The frame F is provided with a cover D which 100 protects the various working parts. The 105 cover D is provided with a non-magnetic cover D which protects the various working parts. The 110

to vibrate by the needle following the groove engraved in the record. The stylus bar vibrates the armature, which is polarized by the permanent magnet H through the pole pieces P P', thus inducing a current or electrical impulses in the coil, which is transmitted to the amplifier. The poles of the U shaped pieces P P' being of opposite polarity adjacent to that end of the armature which is of north polarity will operate one to repel and the other to attract that end of the armature. Similarly one of the poles will repel and the other attract the opposite end of the armature, thus establishing magnetic equilibrium and polarizing the armature. It follows that any slight vibration of the armature disturbs the equilibrium of the magnetic circuit. It is obvious that the above construction will cause the articulate or other sounds which are recorded to be reproduced with great force and distinctness, owing, mainly to the attractive action of the polarized armature upon the poles of the magnet, and this result is obtained when only two opposite poles are used as well as when four are present. The employment of four poles as shown, is preferred, however, because in this construction the attractive and repulsive force of both ends of the armature is used. If for any purpose a stronger field magnet is desired the permanent magnet may be replaced by an electromagnet.

It is obvious that the instrument may be used as a recorder, for the reason that when the coil is connected to the output of a recording circuit and when a current or electrical impulse is sent through the coil W, it magnetizes the armature A. It follows that in the passage of an undulating current through the coil, the armature will be attracted with a force equal to the repulsion and attraction of all four poles, and that the vibratory motion thus produced will be transmitted through the stylus bar to the needle or engraving tool.

The instrument will thus be seen to be equally advantageous for use as a recorder; the magnet having an intensifying action upon the polarized armature which actuates the stylus bar. Such intensifying action will be fourfold in case the polarized armature is hung centrally with both of its ends between opposite polar projections as in the construction illustrated in the drawings. I do not, therefore, wish to be understood as confining my invention to any mere details of construction, because such details may be varied, and are varied by me, without departure from the essence of my invention.

Having thus described my invention, what I claim is:

1. An electromagnetic reproducing device of the phonograph type comprising a field magnet, double pole pieces for said field magnet, one limb of each pole piece acting

upon one end of an armature, and the other limb of each pole piece acting upon the opposite end of said armature, a coil of wire, a split nonmagnetic tube within said coil of wire, a shaft within the core of said coil of wire having freedom of motion about its axis and pivoted in said tube, said core constituting or being identical with said armature, a stylus bar capable of transmitting the vibratory motion of the needle to the armature, or the reverse.

2. An electromagnetic reproducing and recording device of the phonograph type comprising a field magnet, one limb of each pole piece acting upon one end of an armature, and the other limb of each pole piece acting upon the opposite end of said armature, a coil of wire, a split non-magnetic tube within said coil of wire, a shaft within the core of said coil of wire having freedom of motion about its axis and pivoted in said tube, said core constituting or being identical with said armature, a stylus bar capable of transmitting the vibratory motion of the armature through the stylus bar to the needle or engraving tool.

3. An electromagnetic reproducing and recording device comprising a permanent magnet, two pole pieces attached to the permanent magnet, a coil of wire wound around a nonmagnetic spool to an impedance suitable to the electric circuit in which the device is to be used, a centrally pivoted armature operating between the four poles of the two pole pieces and energized by them and connected to a stylus bar with a flexible device for maintaining the balance of the armature.

4. An electromagnetic reproducing and recording device comprising a body ring and casing, a permanent magnet, two pole pieces forming four poles, a coil of wire wound around a nonmagnetic tube to form a spool having through its center an armature which is supported by means of a shaft pivoted through its center in the walls of the tube, and connected with a stylus bar which is capable of being adjusted.

5. An electromagnetic reproducing and recording device of the phonograph type comprising a body ring, a casing, a permanent magnet mounted therein, two U shaped pole pieces attached to the permanent magnet, a coil of wire wound to an impedance (suitable to the electric circuit in which the device is to be used) around a nonmagnetic slotted tube having nonmagnetic end pieces thus forming a spool which spool is fastened within the two pole pieces, an armature within the spool centrally, pivoted with a shaft which is supported in the walls of the nonmagnetic tube, said armature being connected to an adjustable stylus bar which will flexibly maintain the armature in a properly balanced position within said spool.

6. An electromagnetic phonograph repro-

- ducing and recording device comprising an adjustable stylus bar attached to an armature that pivots on a shaft said shaft passing through the center of said armature and supported in holes in the walls of a slotted non-magnetic spool around which is wound a coil of wire, said armature extending beyond the ends of the spool and energized by the four poles of two U shaped pole pieces which are secured to a permanent magnet, said permanent magnet being secured to a body ring in which are also secured two insulated contact lugs for connecting with an electric circuit.
7. An electromagnetic phonograph reproducing and recording device comprising a stylus bar pivoted to a body ring with a device for adjusting said stylus bar, said stylus bar attached to an armature which pivots on a shaft passing through its center thus allow-
- ing for a rotary rather than a lateral movement of the armature, said shaft being supported in holes in the walls of a nonmagnetic tube, said tube being slotted in order to prevent eddy currents of the transformer type, 25 said tube together with nonmagnetic end pieces forming a spool around which is wound, to an impedance suitable to the electric circuit in which the device is to be used, a coil of wire, the ends of the armature extending beyond the ends of the spool and energized by the four poles of the two U shaped pole pieces; said poles being secured to a permanent magnet which is secured to a body ring in which are also secured two insulated contact lugs for connecting with an electric circuit. 30 35

In testimony whereof, I have hereunto set my hand.

HEBER S. NELSON.
